UNITED STATES PATENT OFFICE.

LLOYD A. ANGLE AND JOHN P. SAGER, OF ROCHESTER, NEW YORK, ASSIGNORS TO ART IN
BUTTONS, INCORPORATED, OF ROCHESTER, NEW YORK, A CORPORATION.

BUTTON.

1,303,228.

Specification of Letters Patent. Patented May 13, 1919.

Application filed December 29, 1917. Serial No. 209,396.

To all whom it may concern:

Be it known that we, LLOYD A. ANGLE and JOHN P. SAGER, citizens of the United States, and residents of Rochester, in the county of Monroe and State of New York, have invented certain new and useful Improvements in Buttons, of which the following is a specification.

The present invention relates to buttons, and more particularly to the type in which the button body is formed prior to the connection of the shank thereto, and has the shank secured to it by a bendable anchoring portion deflected into an undercut pocketed portion in the button body, an object of this invention being to provide coöperating portions on the shank and the button body whereby lateral strain on the anchoring portion of the shank is reduced to a minimum.

To this and other ends the invention consists of certain parts and combinations of parts all of which will be hereinafter described, the novel features being pointed out in the appended claims.

In the drawings:

Figure 1 is an enlarged axial section through a button constructed in accordance with this invention;

Fig. 2 is a sectional view through the button body;

Fig. 3 is a plan view of the rear face of the button body;

Fig. 4 is a sectional view through the shank;

Fig. 5 is a perspective view of the shank;

Fig. 6 is a detail view of the shank showing it milled or roughened to prevent turning in the button body;

Fig. 7 is a detail view in section of an embodiment in which the body is made of a substance which will absorb moisture;

Fig. 8 is a detached side view of an embodiment in which the shank is made of two parts; and

Fig. 9 shows the assembled parts of the shank illustrated in Fig. 8.

Referring more particularly to the drawings, 1 indicates a button body made from vegetable ivory, pearl, or the like, and having in its rear face a pocket which has an undercut inner portion 2 and an outer portion 3 of smaller diameter than the undercut portion with its walls perpendicular to the plane of the button body. In this instance,

the walls of the outer portion are cylindrical and the bottom wall of the pocket indicated at 4 is convex.

The shank, which is separately illustrated in Figs. 4 and 5, embodies a portion 5 which may be of any form to permit the attachment of the button, and also embodies the anchoring portion 6 which, before being introduced in the button, is in the form of a flaring cup. Between the anchoring portion and the eye 60 portion 5 is a portion 7 which coöperates with the wall of the outer portion of the pocket in the button in order to give lateral support to the shank to take the strain off the anchoring portion after the latter has 70 been anchored in the button. The shank is preferably formed from a single piece of material, and the anchoring portion thereof is relatively thinner to bend easily, being separated from the supporting portion 7 by 75 an annular groove 8. If desired, the supporting portion 7 and the anchoring portion 6 may have their peripheries roughened or milled to prevent all possibility of rotation between the shank and the button body, as 80 shown at 9 in Fig. 6.

In uniting the shank and the button body, the button body is preferably supported externally and the shank is introduced into the pocket and force is exerted thereon to 85 bend or spread the anchoring portion 6, so that said portion enters the undercut portion 2 of the pocket in the manner shown in Fig. 1, the convex bottom 4 facilitating this spreading. While the shank before being 90 connected to the body of the button has the diameter of its anchoring portion substantially the same as that of the supporting portion 7, the spreading tends to increase the diameter of the anchoring portion so 95 that the shank will be held in the pocket. The walls of the supporting portion 7 being the same as that of the outer wall 3 of the pocket, in this instance, cylindrical, said walls provide coöperating portions which 100 will reduce the lateral strains on the anchoring portion 6 to a minimum.

In Fig. 7 is shown an embodiment of the invention in which the undercut portion 2^a is spaced from the anchoring portion so as 105 to allow for the swelling of the button under moisture when the body 1 is made from vegetable ivory or similar substance which will absorb moisture. The outer portion 3^a of the button body may also be slightly 110

larger than the cylindrical portion 7 of the shank.

In Figs. 8 and 9 is shown an embodiment in which the shank is made of two parts. 5 One of these parts 5^a is in the form of a piece of wire bent into an eye with its ends extended in one direction and parallel, the outer faces of said ends being roughened at 5^b. The other part comprises a body having 10 a cylindrical portion 7^a and a flaring anchoring portion 6^a separated from the supporting portion by an annular groove 8^a, the flaring portion and the supporting portion both being milled or roughened to prevent 15 the turning of the shank in the button body. The body of the shank has an axial bore 7^b and in this bore the parallel ends of the eye 5^a are introduced, being held therein by solder 7^c, the roughened faces 5^b of the ends 20 serving to anchor such ends in the solder. This embodiment is attached to the button body in the same manner as the other embodiment.

What we claim as our invention and desire to secure by Letters Patent is:—

1. A button comprising a body portion formed with a pocket in its rear face, said pocket having an undercut portion and a cylindrically formed wall extending from 25 said undercut portion to the rear face of the button, the diameter of the outer por-

tion of the pocket being less than that of the undercut portion, and a shank having an eye portion, an anchoring portion, and a connecting portion between the eye portion and the anchoring portion, the anchoring portion being formed with a portion fitting in the undercut portion of the pocket and also with a cylindrical portion of less diameter than the portion projecting into the 40 undercut portion of the pocket, said cylindrical portion fitting the cylindrical wall of the pocket, the portions of the shank connecting the eye portion and the cylindrical portion being less in diameter than the cylindrical portion. 45

2. A button comprising a body portion formed with a pocket in its rear face, said pocket having an undercut portion and a cylindrically formed wall extending from 50 said undercut portion to the rear face of the button, and a shank formed of a wire portion provided with an eye and two ends, and an anchoring portion projecting into the undercut portion and having a cylindrically formed portion fitting the cylindrically formed wall of the pocket, the cylindrically formed portion receiving the ends of the wire portion.

LLOYD A. ANGLE.
JOHN P. SAGER.
